UNITED STATES PATENT OFFICE.

BARNEY T. CORNETT, OF SHOWNS, TENNESSEE, ASSIGNOR TO MAURICE E. FARRIS, OF SHOWNS, TENNESSEE.

SEALING-TORCH.

1,078,903.

Specification of Letters Patent.

Patented Nov. 18, 1913.

Application filed May 11, 1912. Serial No. 696,737.

To all whom it may concern:

Be it known that I, BARNEY T. CORNETT, a citizen of the United States, residing at Showns, in the county of Johnson and State of Tennessee, have invented new and useful Improvements in Sealing-Torches, of which the following is a specification.

This invention relates to sealing torches, the object in view being to provide a device which will greatly facilitate the melting of a bar of wax, preparatory to applying the wax in a heated condition to the wrapper of any package, the arrangement being such that the fingers of the operator are protected and kept from coming into contact with the hot wax.

With the above and other objects in view, the invention consists in the construction, combination and arrangement of parts, as will be hereinafter more fully described, illustrated in the accompanying drawings, and pointed out in the claims hereunto appended.

In the drawings: Figure 1 is a side elevation of the sealing torch. Fig. 2 is a plan view of the same.

The sealing torch contemplated in this invention comprises essentially an oil font or reservoir 1, leading off from which is a spout or wick tube 2, in which is a wick 3 which leads into the oil and obtains a constant supply therefrom. Extending upward from the top of the font or reservoir 1 is a pivot post 4, upon which is mounted a horizontally movable wax carrier 5, the same being provided with eyes 6, which embrace the post 4 and adapt the carrier to be swung upon said post as a pivotal center.

In the preferred embodiment of this invention, and for the sake of economy, the carrier 5 is made of suitable length of wire, bent and twisted to form the eyes which embrace the pivotal post, and an outwardly extending pair of spring jaws 7 oppositely deflected, as shown at 8, to embrace the bar of sealing wax indicated at 9, the arms being of such length as to carry the end of the bar of wax over the flame of the burner.

In rear of the pivot post, the carrier is provided with a finger loop or ring 10, in which the finger of the operator may be placed for the purpose of swinging the carrier and carrying the bar of wax toward

and away from the flame. The font is also provided at a suitable point with a handle or finger loop 11, through which one finger of the hand may be placed, while another finger is placed through the loop of the carrier. This enables the operator to obtain a firm hold on the torch, and at the same time to swing the carrier for the purpose set forth.

12 designates a drip cup or trough which is arranged under the path traveled by the bar of wax, said trough being connected to the spout or wick tube by means of an arm 13. This trough reaches to a point near the burner, so as to catch any drippings from the bar of wax in case of overheating the latter.

It will be understood from the foregoing description, taken in connection with the accompanying drawings, that the wax bar may be readily shifted to a position over the flame, until it is sufficiently heated, and then be carried away from the flame by the pivoted carrier, so that the wrapper of a package may be moved along in contact with the heated end of the bar of wax, after which the bar is moved backward to a position over the drip trough, the latter catching any drippings from the wax and preventing the same from falling upon the desk, table or other support on which the torch is placed.

What is claimed is:

1. A sealing torch, comprising an oil font, a burner, a sealing wax carrier pivotally mounted on the font to adapt the wax to be swung toward and away from the burner, and a drip trough arranged under the path of the wax, and supported by the burner.

2. A sealing torch comprising an oil font, a finger loop on said font, a burner, a sealing wax carrier pivotally mounted on the font to swing toward and away from the burner on a vertical axis, and a finger loop on said carrier for use jointly with the first-named finger loop.

In testimony whereof I affix my signature in presence of two witnesses.

BARNEY T. CORNETT.
